CLAIM

I claim the ornamental design for a dog house-shaped hot dog bread roll, as shown and described.

DESCRIPTION

FIG. 1 is a front, top, right side perspective view of a dog house-shaped hot dog bread roll, shown in an environmental use;

FIG. 2 is a front, top, right side perspective view thereof;

FIG. 3 is a front elevation view thereof;

FIG. 4 is a rear elevation view thereof;

FIG. 5 is a top plan view thereof;

FIG. 6 is a right side elevation view thereof, the left side being a mirror image thereof;

FIG. 7 is a bottom plan view thereof; and,

FIG. 8 is a front, top, right side perspective view thereof, shown in an environment of use.

The broken lines shown in FIGS. 2, 3, 5 and 6 illustrate portions of the dog house-shaped hot dog bread roll that form no part of the claimed design. The broken lines illustrating the person, hot dog, condiments, spoon and bottle in FIGS. 1 and 8 are environment, while the remaining broken lines in FIGS. 1 and 8 illustrate portions of the dog house-shaped hot dog bread roll that form no part of the claimed design.

The more concentrated stippled shading and less concentrated stippled shading shown in FIGS. 1-4 and 8 represent a contrasting appearance.
